CLAIM

The ornamental design for a cover for bedside commode, as shown and described.

DESCRIPTION

FIG. 1 is a front perspective view of a cover for a bedside commode showing my new design;

FIG. 2 is a left side elevational view thereof;

FIG. 3 is a top plan view thereof;

FIG. 4 is a front elevational view thereof; and

FIG. 5 is a rear elevational view thereof.

The broken lines representing the commode are shown for illustrative purposes only.
